TUNNEL KILN.

Application filed November 23, 1925. Serial No. 70,775.

This application is a continuation in part of our prior application Serial No. 13,884, filed March 7, 1925, the disclosure contained in this application being identical with that of the prior application referred to except for the addition of a further description of the preferred material of which certain stationary floor plates in the muffles are constructed and the description of a detail 10 illustrated but not specifically described in the earlier application.

Among the objects of the improved tunnel kiln which we have invented and which we describe and claim herein are economy in 15 construction and operation and uniformity in the application of heat to all parts of the charge being fired. In tunnel kilns as heretofore constructed it has been the practice to load the charge upon cars which are 20 pushed through the kiln, the kilns for most purposes being of great length, two to three hundred feet and more and containing a correspondingly long train of cars loaded with material being fired. The cars run upon 25 rails laid on the floor of the tunnel. It is, of course, necessary to protect the trucks and the metal structural elements of the under-frames of the cars from the excessive heat to which the ware carried by them is subjected, and this is accomplished by providing 30 the floors of the flat-topped cars with a layer of material of low heat conductivity and providing a sand seal or other form of seal at about the level of the car floor between the car and the side walls of the tunnel. The floor of the car is the conveyor 35 platform and the heat must be applied exclusively to the space above the conveyor platform in order to avoid injury to the structural elements and running gear below. In 40 many instances it is necessary that heat be applied below as well as at the sides and top of the charge being fired, and this has heretofore been accomplished by carrying the ware on a refractory floor, elevated above 45 the car floor, and supported on open work through which the heated air or products of combustion have access to the space beneath the ware. In order to afford space for cars of a capacity that would justify the cost of 50 kilns of this type used for the manufacture of tile, brick, pottery, sanitary ware, etc., it has been necessary to make the interior

width of the tunnel not less than four feet, and from that upward to fifteen feet in 55 kilns for the manufacture of common brick. The height of these tunnels above the car floor ranges from a little over the width up to twice the width, except in the case of the very wide kilns for common brick some of 60 which are of less height than width. The result is a minimum interior cross-sectional area four feet square and a charge of ware to be fired having substantially the same cross-sectional area. Whether the ware is 65 inclosed in saggers or set in open formation it has been found impossible to impart a uniform temperature throughout a mass of such large cross-sectional area. The inequality in heating is frequently so great that the 70 shrinkage of ware at the bottom and sides before like shrinkage has taken place in the ware at the top makes the mass insecure and causes it to topple over. In some instances the tops of the cars have been given a pitch 75 of a half-inch toward the center in an endeavor to counteract the tendency of the ware to topple over from this uneven shrinkage. Furthermore the refractory tops of the cars are constantly expanding and contracting as the cars move through the tunnel and are taken from the tunnel for unloading and reloading thus necessitating frequent replacement. The initial cost of tunnel kilns of such large dimensions and the 80 large equipment of cars constitutes a heavy item of expense in the manufacture of ceramic articles.

By means of our invention described and claimed herein we greatly reduce the initial 85 cost of the kiln without reducing its capacity proportionately and at the same time render possible and practicable a much more uniform heating of all parts of the charge than has been possible or practicable 90 in kilns of the type above described. Our improved kiln possesses the further advantage of dividing a given output among several kilns in place of firing it all in one kiln of the large dimensions heretofore used, thus 95 minimizing the damage consequent upon any irregularity or accident in the operation of one of the kilns.

In our improved kiln the firing chamber 100 through which the ware is moved is provided with a stationary floor to the under

side of which the heated gases have access, this floor in the kiln herein described forming part of a continuous muffle extending from end to end of the kiln and being heated at the sides and top as well as at the bottom. The ware to be fired is set upon rectangular slabs of a suitable refractory material. Each slab with its charge set on it is placed on an exterior extension of the muffle floor and pressure exerted on it by a plunger moves it into the muffle and imparts movement to all of the slabs already in the muffle, all of them being in contact, edge to edge. The movement of the plunger is timed to give the material the proper time of firing in its passage through the tunnel. Additional slabs with their charges loaded upon them are introduced by withdrawing the plunger sufficiently to make space for placing the additional slab upon the exterior extension of the muffle floor between the last preceding slab and the plunger. By means of this construction, we have eliminated the initial cost and the expense of maintenance of the cars heretofore used in tunnel kilns, and have at the same time made it possible to economically construct and operate a tunnel kiln of sufficiently small cross-sectional area to secure uniformity in the heating of different parts of the charge. While it might be theoretically possible to construct and operate a tunnel kiln of small cross-section with cars of the usual type and might be economically possible to do so in the manufacture of articles commanding a sufficiently high price, such a kiln would greatly exceed our improved kiln in cost of construction, maintenance and operation, and in such a kiln the ware could be heated from the under side only by supporting it on open work built up on the car floor, thus reducing the useful capacity of the kiln to that extent, whereas in our improved kiln heat is applied directly beneath the floor and communicated therethrough and through the supporting conveyor slab to the ware. In our improved kiln there is a uniform communication of heat to the ware from all four sides of the muffle.

50 In the drawings:

Figure 1 is a side elevation of our improved kiln.

Figure 2 is a sectional plan view on the broken line A—A of Figure 1.

55 Figure 3 is an end elevation, the left-hand part being broken away on the line B—B of Figure 2.

Figure 4 is a section on the line D—D of Figures 1 and 2.

60 Figure 5 is a fragmentary section on the line C—C of Figure 1.

Figures 6 and 7 show a drive mechanism.

We have shown the kiln in the drawings elevated to a convenient working height upon the foundations 1 and I-beams 2.

The muffles 3 and 4 extend throughout the length of the kiln and are formed of slabs 5 of refractory material. Between the two muffles, which are parallel, there is a flue space 6 extending longitudinally of the kiln from a point adjacent the charging end E to a connection with flue 6' of reduced cross-section (Figure 4) which latter leads to the stack F. The construction surrounding the muffles adjacent the charging end of the kiln is clearly shown in Figure 2, and in the left-sectional part of Figure 3. The lower part of the kiln construction is composed of several layers of brick, six courses being shown in the kiln illustrated. The muffles are supported upon the upper part of the under-work of brick. Along the inner adjacent sides the muffles are supported upon solid walls of refractory brick G. At the outer sides the muffles are supported upon an open work structure of refractory brick or blocks 7, there being free spaces between the members 7 to afford free passage for the heated gases. The exterior walls 8 of the kiln and also the end walls are built up on the under-work of brick. Directed into openings in the side walls of the kiln between the charging end and the high heat chamber 20 we have shown eight burners, 12, 12, 13, 13, 14, 14, 15, 15, four upon each side. The design of the kiln and the features constituting our invention may be adapted to the use of gas, oil or solid fuel for heating.

Immediately adjacent each of the burner openings and upon the side thereof remote from the charging end of the kiln, the left-hand end as viewed in Figures 1 and 2, we have provided dividing walls 17 which extend transversely of the kiln across the spaces 16, 9 and 11 at the bottom, outer side and top of the muffles. At the top of the muffles, walls 17 terminate at the line 18, Figure 3, thus leaving the flue 6 unobstructed. This has the effect of dividing the space at the bottom, outer sides and over the tops of the muffles into four compartments which have no communication with each other except by means of the central flue 6. As indicated in Figure 3, the gases and products of combustion from the burners pass into and through the openings provided for them and thence beneath the muffles where they impinge upon the walls G and flow back to the vertical passages 9 and over the tops of the muffles and through the spaces 11. During this part of their circulation the heated gases are confined to the space between adjacent cross-walls 17. Upon passing beyond the edge 18 of the part of the partition 17 above the muffle the gases enter the center longitudinal flue 6 which conducts the gases of all the burners toward the stack.

As indicated in Figures 2 and 4, the high heat chamber is wider than the pre-heating part of the kiln. We have shown two burn-

ers, 21, on each side of the high heat chamber, and, as indicated in Figure 4, the burning gases and products of combustion from burners 21 circulate beneath the muffles, 5 thence pass upward at the outer sides and over the top thereof, whence they sweep downward into the space between the muffles and through the opening 22 in the end wall 40 of the high heat chamber to a duct 10 wall 40 of the high heat chamber to a duct leading under one of the muffles to the stack F as indicated in dotted lines in Figure 2. From the charging end E of the kiln to the end wall 23 of the high heat chamber the flue 6 extends from the top of the kiln to the 15 foundation brick upon which the muffles are supported, as shown in Figure 3. The wall 23 extends across the upper part of the flue 6 and down to a horizontal partition 24 which extends the length of the high heat 20 chamber 20. The flue 6 communicates with the space beneath the horizontal partition 24 through an opening in wall 23, thus confining the gases from the pre-heater burners to the space beneath partition 24, designated 25 6' on Figure 4. The horizontal partition 24 terminates at the end wall 40 of the high heat chamber, and the gases flowing through the flue 6' pass through an opening in end wall 40. The gases from the pre-heating 30 burners and the high heat burners thus come together just beyond wall 40, whence they flow through a duct beneath one of the muffles to the stack F as indicated in dotted lines in Figure 2.

35 We make the part of the muffles extending through the high heat chamber wider than the end parts as indicated at 26, Figures 2 and 4, for the purpose of providing extra space in the high heat zone with a view to 40 minimizing the danger of the operation of the kiln being obstructed by the toppling over of any of the ware in this part of the kiln.

45 In the bottom of the muffles we provide a lining 27 of refractory material provided at its edges with upwardly extending flanges 48 adjacent the side walls of the muffle. The lining 27 and side flanges 48 extend straight through the muffles from end to end.

50 The means for carrying the ware to be fired through each of the muffles consists of a series of rectangular plates 28, which abut edge to edge and form a continuous movable floor extending through the muffle and resting 55 on the refractory floor lining between the side flanges 48 thereof. As indicated at 30 in Figures 1 and 2, we provide exterior extensions of the tracks formed by the linings 27 in the bottoms of the muffles. These extensions 30 are outside of the zone of heat and may be constructed of metal. In charging the kiln a plate 28 is placed upon the track 30 at the charging end of the kiln and then pushed into the muffle, a second plate 60 is then similarly loaded with ware and moved to a position with its edge abutting against the edge of the previously charged plate, and this procedure is repeated as rapidly as the predetermined rate of movement of the charge through the muffle makes room 70 for the insertion of a new plate with its load of ware at the charging end. The series of plates in the muffle are moved forward by exerting pressure upon the last plate to be charged, the pressure being transmitted from plate to plate through their abutting edges thus imparting movement to the entire series. Pressure may be applied to the conveyor plates by any suitable mechanism geared to move the ware at the proper rate for the time of firing necessary. We have shown for this purpose plungers 29 which may be temporarily withdrawn a sufficient distance to permit insertion of an additional plate 75 between the plunger and the last previously charged plate, and then again clutched to the gearing by which it is moved forward at the rate necessary to move the series of plates through the muffle at the proper speed.

80 We have found that carborundum is a suitable material for the conveyor plates 28, this material possessing the necessary strength at high temperatures to transmit through the series of plates the pressure by which they are moved, and our investigations 85 also indicate that the friction is less when the movable plates and the stationary track beneath them are not constructed of the same material and for this reason we prefer to construct the lining 27 forming the track of a refractory material other than carborundum. We have obtained the best results by constructing one of the parts between which the movement takes place of vitrified material. In practice we have used floor plates 90 27 constructed of a refractory mixture of the type used for muffles and for refractory brick but burned at a temperature higher than that used in our kiln and thereby 95 wholly or partially vitrified. The carborundum plates 28 move over the vitrified floor plates 27 with relatively little friction and wear, and as the floor plates 27 remain at a substantially constant temperature they are 100 not subject to deterioration from contraction and expansion due to temperature changes. The carborundum plates 28 are not injuriously affected by the changes of temperature to which they are subjected or by the pressure 105 which they undergo when moved through the kiln as above described. In starting the kiln, and sometimes at intervals thereafter, we find it advantageous to provide a layer 110 of silica sand or quartz powdered to about 115 16 mesh between the carborundum plates 28 and the lining 27 in order to reduce the friction, but in operation sufficient powdered material for this purpose will generally be 120 formed by the abrasive action between the conveyor plates and the lining.

In Figures 6 and 7, we show means for imparting movement to the movable floor wherein the drive shaft 50, by means of screw 51 fixed thereto, rotates screw gear 52 and shaft 53. Conical clutch member 54 is fixed to shaft 53. Pinion 55 is formed with a co-acting conical clutch member and is loose on shaft 53 when not clutched thereto by the conical clutch. Hand wheel 56 is screw-threaded on shaft 53 and affords means for engaging and disengaging the clutch at will. Pinion 55 meshes with gear 57 which is fixed to shaft 58. Pinion 59, fixed to shaft 58, meshes with gear 60, fixed 10 to shaft 61, to which pinion 62 is also fixed. Pinion 62 meshes with rack 63 which, with its head 64, forms the plunger which bears against the last conveyor plate 28 and thus moves the series of plates 28 constituting 15 the movable floor of the kiln. When a new plate with its charge of ware is to be introduced into the kiln the clutch is released by turning the hand wheel 56 and shaft 61 is manually rotated by means of handle 65 on hand-wheel 66 in the reverse direction, thus 20 through pinion 62, withdrawing the rack and its plunger head 64 to make room for the introduction of an additional conveyor plate 28. Hand-wheel 66 is then rotated by 25 hand in the direction of the power drive to bring plunger 64 against the newly introduced plate 28, then clutch 55-54 is engaged by means of hand-wheel 56, thus restoring the power drive to operation.

In Figure 1, we have shown two openings 32, 33, which extend through the outer wall 8 of the kiln and through the wall 5 of the muffle. As shown in Figure 5, sleeves 35 of refractory material are fitted to the 30 aligned openings in the walls 8 and 5 and extend across the space therebetween. During the operation of the kiln the outer end of the sleeves 35 may be closed by bricks loosely placed therein. In the event that, 35 because of disarrangement of the ware in the muffle or for other reasons, it becomes necessary or desirable to gain access to the interior of the muffle, the bricks may be removed from the openings formed by the sleeves 35 and the contents of the muffle may then be manipulated by suitable implements, the sleeves serving to confine the gases to the space between the muffles and exterior walls and to protect the implements from 40 the direct action of the heat.

What we claim as our invention is:

1. In a tunnel kiln, a stationary floor constructed of vitrified material, means for applying heat beneath said floor and conveyor means above said floor for moving material to be fired through the tunnel of said kiln.
2. In a tunnel kiln, a stationary floor constructed of vitrified material, a movable floor above said stationary floor, means for

applying heat beneath said stationary floor, and means for moving said movable floor through said tunnel.

3. In a tunnel kiln, a stationary floor constructed of vitrified material, a movable floor comprising a series of plates above said stationary floor, and means for applying pressure to said plates to move the same through said kiln.

4. In a tunnel kiln, a stationary floor constructed of vitrified material, means for applying heat beneath said floor, a movable floor comprising a series of plates above said stationary floor, and means for applying pressure to said plates to move the same through said kiln.

5. In a tunnel kiln, a muffle having a stationary floor of vitrified material, a movable floor resting on said stationary floor, and means for moving said movable floor through said muffle.

6. In a tunnel kiln, a plurality of muffles arranged side by side with spaces intervening between said muffles and between said muffles and the top, bottom and side walls of said kiln, and means for applying heat through said spaces to all sides of said muffles.

7. In a tunnel kiln, a muffle having a stationary floor of vitrified material, a movable floor resting on said stationary floor, said muffle and floor being constructed of refractory material, said movable floor comprising a series of plates and means for applying pressure to said plates to move the same through said muffle.

8. In a tunnel kiln, a muffle, means for applying heat to both sides and the top and bottom thereof, and means inside of said muffle for moving material to be fired there-through, the part of said means within said muffle being constructed of refractory material.

9. In a tunnel kiln, a muffle, means for applying heat to both sides and the top and bottom thereof, a refractory movable floor inside of said muffle and means for moving said floor through said muffle.

10. In a tunnel kiln, a muffle, means for applying heat to both sides and the top and bottom thereof, a movable refractory floor inside of said muffle comprising a series of plates and means for applying pressure to said plates to move the same through said muffle.

11. In a tunnel kiln, a stationary floor, a movable floor above said stationary floor, said floors being constructed of different refractory materials, means for applying heat beneath said stationary floor, and means for moving said movable floor through said tunnel.

12. In a tunnel kiln, a stationary floor, a movable floor comprising a series of plates above said stationary floor and means for

applying pressure to said plates to move the same through said kiln, said floors being constructed of different refractory materials.

13. In a tunnel kiln, a stationary floor, means for applying heat beneath said floor, a movable floor comprising a series of plates above said stationary floor, said floors being constructed of different refractory materials, and means for applying pressure to said plates to move the same through said kiln.

14. In a tunnel kiln, a muffle, a movable floor inside of said muffle, said floor and the inner bottom surface of said muffle being of different refractory materials, and means for moving said movable floor through said muffle.

15. In a tunnel kiln, a muffle, a movable floor inside of said muffle, said floor and the inner bottom surface of said muffle being of different refractory materials, said movable floor comprising a series of plates, and means for applying pressure to said plates to move the same through said muffle.

16. In a tunnel kiln, a muffle, means for applying heat to the sides, top and bottom thereof, a movable floor inside of said muffle, said floor and the inner bottom surface of said muffle being of different refractory materials, and means for moving said floor through said muffle.

17. In a tunnel kiln, a muffle, means for applying heat to the sides, top and bottom thereof, a movable floor inside of said muffle comprising a series of plates, said floor and the inner bottom surface of said muffle being of different refractory materials, and means for applying pressure to said plates to move the same through said muffle.

18. In a tunnel kiln, a stationary floor, a movable carborundum floor above said stationary floor, means for applying heat beneath said stationary floor, and means for moving said movable floor through said tunnel.

19. In a tunnel kiln, a stationary refractory floor, a movable floor comprising a series of carborundum plates above said stationary floor and means for applying pressure to said plates to move the same through said kiln.

20. In a tunnel kiln, a stationary floor of vitrified material, a movable floor comprising a series of carborundum plates above said stationary floor and means for applying pressure to said plates to move the same through said kiln.

21. In a tunnel kiln, a stationary refractory floor, means for applying heat beneath said floor, a movable floor comprising a series of carborundum plates above said stationary floor, and means for applying pressure to said plates to move the same through said kiln.

22. In a tunnel kiln, a stationary floor of vitrified material, means for applying heat

beneath said floor, a movable floor comprising a series of carborundum plates above said stationary floor, and means for applying pressure to said plates to move the same through said kiln.

23. In a tunnel kiln, a muffle, a movable carborundum floor inside of said muffle, and means for moving said movable floor through said muffle.

24. In a tunnel kiln, a muffle having a stationary floor of vitrified material, a movable carborundum floor inside of said muffle, and means for moving said movable floor through said muffle.

25. In a tunnel kiln, a muffle, a movable carborundum floor inside of said muffle, said movable floor comprising a series of plates and means for applying pressure to said plates to move the same through said muffle.

26. In a tunnel kiln, a muffle having a stationary floor of vitrified material, a movable carborundum floor inside of said muffle, said movable floor comprising a series of plates and means for applying pressure to said plates to move the same through said muffle.

27. In a tunnel kiln, a muffle, means for applying heat to the sides and top thereof, a movable carborundum floor inside of said muffle and means for moving said floor through said muffle.

28. In a tunnel kiln, a muffle having a stationary floor of vitrified material, means for applying heat to the sides and top thereof, a movable carborundum floor inside of said muffle and means for moving said floor through said muffle.

29. In a tunnel kiln, a muffle, means for applying heat to the sides, top and bottom thereof, a movable carborundum floor inside of said muffle comprising a series of plates and means for applying pressure to said plates to move the same through said muffle.

30. In a tunnel kiln, a muffle having a stationary floor of vitrified material, means for applying heat to the sides, top and bottom thereof, a movable carborundum floor inside of said muffle comprising a series of plates and means for applying pressure to said plates to move the same through said muffle.

31. In a tunnel kiln, a stationary floor constructed of vitrified material, a movable floor supported on said stationary floor, a layer of loose comminuted material between said stationary and movable floors, and means for moving said movable floor through said kiln.

32. In a tunnel kiln, a stationary floor constructed of vitrified material, means for applying heat beneath said stationary floor, a movable floor supported on said stationary floor, a layer of loose comminuted material between said stationary and movable floors,

and means for moving said movable floor through said kiln.

33. In a tunnel kiln, a stationary floor constructed of vitrified material, a movable floor supported on said stationary floor, a layer of loose comminuted material between said stationary and movable floors, and means for moving said movable floor through said kiln.

34. In a tunnel kiln, a stationary floor constructed of vitrified material, means for applying heat beneath said stationary floor, a movable floor supported on said stationary floor, a layer of loose comminuted material between said stationary and movable floors, and means for moving said movable floor through said kiln.

35. In a tunnel kiln, a stationary floor, a movable carborundum floor supported on said stationary floor, a layer of loose comminuted material between said stationary and movable floors, and means for moving said movable floor through said kiln.

36. In a tunnel kiln, a stationary floor, means for applying heat beneath said stationary floor, a movable carborundum floor supported on said stationary floor, a layer of loose comminuted material between said stationary and movable floors, and means for moving said movable floor through said kiln.

37. In a tunnel kiln, a stationary floor, a

movable floor consisting of carborundum plates supported on said stationary floor, a layer of loose comminuted material between said plates and stationary floor, and means for moving said plates through said kiln.

38. In a tunnel kiln, a stationary floor, a movable floor consisting of carborundum plates supported on said stationary floor, a layer of loose comminuted material between said plates and stationary floor, means for applying heat beneath said stationary floor and means for moving said plates through said kiln.

39. In a tunnel kiln, exterior and interior walls with a heating space therebetween, said exterior and interior walls having opposed openings therein, a tubular housing of refractory material extending through said openings and across said space, and removable means for closing the opening through said housing.

40. In a furnace of the class described, a muffle, a movable floor in said muffle, means for moving said floor through said muffle, independently controllable sources of heat coacting with separate successive sections of the walls of said muffle.

In witness whereof, we have subscribed our names this 5th day of November, 1925.

THEODORE C. PROUTY.
